COOLING METHOD AND APPARATUS

Herman W. Kleist, Chicago, Ill., assignor to Dole
Refrigerating Company, Chicago, Ill., a cor-
poration of Illinois

Application January 2, 1936, Serial No. 57,178

20 Claims. (Cl. 62—126)

This invention relates to cooling method and apparatus and has for its object to provide a new and improved device of this description.

The invention has as a further object to provide a cooling method and apparatus wherein a liquid refrigerant can be congealed without injury to the container.

The invention has as a further object to provide means for satisfactorily using a liquid refrigerant in a thin container.

The invention has as a further object to provide a container for a liquid refrigerant consisting of plates of heat conducting material, preferably metal, with the cooling coil between them, with a liquid refrigerant between the plates, and with means for permitting the refrigerant when congealed to expand without injuring the plates.

The invention has other objects which are more particularly pointed out in the accompanying description.

Referring now to the drawing,

Fig. 1 is a view showing one form of device embodying the invention, with parts broken away;

Fig. 2 is a sectional view taken on line 2—2 of Fig. 1, on an enlarged scale;

Fig. 3 is a sectional view showing one form of vacuum nipple;

Fig. 4 is a view showing a modified construction; and

Fig. 5 is a view showing a further modified construction.

Like numerals refer to like parts throughout the several figures.

One of the difficult problems in refrigeration has been to provide a refrigerating device which contains a liquid refrigerant, which liquid refrigerant is to be congealed at a very low temperature and held at this low temperature. In such devices heretofore it has not been possible to get a uniform temperature on the outside and it has been difficult to hold the liquid refrigerant and to keep the sides from bulging out and when the liquid refrigerant congeals it has been practically impossible to prevent injury to the device by the expansion. Another problem has been the difficulty of securing an efficient heat transfer relationship between the contacting metal parts of the apparatus. This present device obviates all these difficulties.

In carrying out my invention, I provide a tank made up of two separated plates 2, 3 of heat conducting material, such as metal, which are connected together at the edges so as to form a hermetically sealed compartment between them.

Within this compartment are provided pipes 4 and 5 having at intervals spacers 6 between them, the pipes being in contact with the plates 2 and 3. The pipes may be arranged in coils or in any other form and may be placed as close together as desired, or a distance apart, depending upon the conditions presented. A cooling fluid is passed through these pipes so as to cool them and any suitable cooling fluid may be used. The pipes 4 and 5 are connected to the source of fluid supply in any desired manner, as by means of the nipple 7. In the construction illustrated a continuous pipe is used and is bent back and forth between the plates, and the cooling medium passes in through one nipple 7 and out through the other nipple 7. In the space between the plates 2 and 3 is placed a liquid refrigerant 8. All of the known eutectic solutions which I contemplate using have an appreciable vapor pressure at the temperature of the containing unit and of the eutectic contained therein. This liquid refrigerant does not entirely fill the space between the plates 2 and 3, but there is left a space 9 free of the refrigerant. When liquid refrigerant is placed between the two plates with a cooling coil between them, it pushes out the plates, causing them to bulge and when the liquid congeals the plates are often ruptured.

Air is exhausted from between the plates 2 and 3 in any desired manner, as by connecting the nipple 10 with a vacuum producing device. This withdraws the air from the space 9. The amount of air withdrawn from between the plates will depend upon the result desired, but it should be sufficient to provide such a difference in pressure between the interior and the exterior of the plates as to cause the plates to be pressed against the coils of the pipe and to be properly held when the liquid between the plates congeals. There is also air intermingled with the liquid refrigerant 8 which causes an uneven temperature on the face of the plates 2 and 3. The vacuum in the space between the plates, withdraws the air from the liquid refrigerant so that it is substantially free of air, so that there will be even temperatures over the face of the plates. In the preferred form the space 9 is substantially free of air, a vacuum plate being thus produced. Thus vacuum causes the plates 2 and 3 to be tightly pressed against the pipes 4 and 5.

When the liquid refrigerant or cryohydrate is congealed it expands up into the space 9. If there were air at atmospheric pressure in this space,

the air would be compressed and the pressure inside of the device would be greatly increased, and this pressure often causes injury or rupture of the parts. With this vacuum arrangement 5 when the liquid refrigerant is congealed it simply expands up into the vacuum, that is the space 9, and since there is no air in this space there is no increase in pressure and danger of rupture or injury to the parts by congealing of the liquid refrigerant is thereby avoided. Furthermore, by removing the air from the liquid refrigerant a uniform temperature throughout 10 the surface of the plate is secured.

The tank is filled up to any desired height, 15 preferably about nine-tenths of its total capacity, with any of the refrigerant liquids desired. This liquid refrigerant is then frozen solid in order to increase its latent heat over the regular solution. This solution without freezing, for example, might have a latent heat of 12 to 15 20 B. t. u.'s per pound and when frozen into a solid mass and then thawed, the latent heat per pound will be as high as 105 B. t. u.'s. These liquid refrigerants often have intermingled with them, in addition to air, different kinds of gases 25 and by exhausting the air these gases are also exhausted. These gases and the air decrease the efficiency of the refrigerant and when they are removed its efficiency is increased. By eliminating these different gases corrosion of the 30 tank is prevented. This corrosion has been quite a problem heretofore. This device is exceedingly effective with a brine solution as heretofore in the tanks used it has been impossible to keep the brine solution free from air. I have 35 found by numerous tests that one advantage of having the two sets of coils 4 and 5 in the tank is that the plates 2 and 3 may be spaced farther apart and a larger tank thus provided, and therefore more eutectic solution can be used than 40 is the case where a single coil is used with the plate 2 engaging one side of the pipe and the plate 3 engaging the other side of the pipe. By using the greater amount of eutectic solution, the efficiency of each tank is increased. When 45 a single coil is used, the size may be varied, depending upon the conditions presented. I have secured satisfactory results with pipe ranging from three-eighths inch to one inch in diameter.

Any desired form of vacuum nipple may be 50 used. I have shown a vacuum nipple 10 which has an enlarged recess 11 and a check valve 12 in said recess and normally closing the passageway 13. Each time the vacuum withdrawing device is operated, the valve lifts so as to let air and gas pass out and then drops to close 55 passageway 13 against re-entrance of air. When the desired vacuum is produced, the plug 14 is then placed in position to further prevent the entrance of air. The vacuum used is preferably a high vacuum, the preferred form being a 60 vacuum of about twenty-eight inches.

In Fig. 4 there is shown a modified construction where there is a hermetically sealed tank 65 having the plates 2a and 3a joined together to form a hermetically sealed tank and the pipe or coil 15 placed in the center and the spacers 16 and 17 on each side, which engage the pipe and which also engage the plates 2a and 3a. The liquid refrigerant 18 is placed in the tank 70 leaving a space 19 at the top and the air is then exhausted as hereinbefore set out.

In Fig. 5 I have shown a modified construction where there is a vacuum tank 20 in the 75 middle and it is surrounded by the vacuum tank

21, there being the spacers 22 and 23 between the vacuum tank 20 and the walls of the vacuum tank 21. The vacuum tank 20 simply has the air exhausted and the vacuum tank 21 is partially filled with the liquid refrigerant 24 and has the space 25 which is free from liquid refrigerant and the air is exhausted from this space and from the liquid refrigerant as hereinbefore set out.

The tight pressing of the plates against the 10 pipes or the spacers due to the vacuum inside the tank provides a smooth surface on each side of the tank. In view of the fact that the temperature of this tank is often very low and may be kept at about thirty degrees below zero for 15 long periods, frost may accumulate on the plates, but it can be easily scraped off as it only loosely adheres to the surface and any slight brushing dislodges it. In all cases there is a vapor present and in all cases a film of condensed 20 vapor lies against all surfaces of metal within the unit, covering all surfaces of the pipe coils and all surfaces of the intermediate metal members and the inner surfaces of the plates and the end sections. This film is very hard and 25 when two of the films on the two surfaces are brought together the two films under pressure partially coalesce and form what is called the "wringing film." Such films are very hard, having high compression strength and because of 30 their extreme thinness and other physical characteristics possess a much higher coefficient of heat conductivity than the free liquid of which they are composed. There is therefore provided between the metal parts of the refrigerating unit 35 a direct thermal contact which in every way is one having capabilities of heat conduction approaching if not actually equaling the heat conduction of integral metal construction. This film between two members of the unit has been measured and has a thickness of approximately two 40 times the radius of molecular attraction. In other words, its thickness is approximately one and two-tenths of a millionth of an inch.

This device can be used wherever desired. One of the important uses is for use in trucks and 45 in connection with the storage and sale of ice cream and in any other place where it is desired to have low temperatures and to maintain a low temperature for a long period. For example, when the device is used in trucks, the liquid refrigerant may be frozen at night and then the truck used to deliver ice cream or any other material, the frozen liquid refrigerant maintaining the temperature for many hours, as for example through the entire day, the refrigerant 50 gradually melting and then being again frozen and the same operation repeated.

I claim:

1. A cooling apparatus comprising two separated plates, cooling means between said plates, the plates being hermetically sealed so as to provide a tank, said tank being partially filled with a liquid refrigerant so as to leave a space above it, the air being substantially all exhausted from 60 said tank when the liquid refrigerant is therein, so as to tightly press the sides of the tank against said cooling means and remove air from the liquid refrigerant and provide a high vacuum above the liquid refrigerant into which it can expand 65 when congealed.

2. A cooling apparatus comprising two separated plates, two separated sets of cooling coils between the plates, one engaging one plate and the other the other plate, separating devices be- 70 75

5. between said coils to hold them separated against pressure, the plates being hermetically sealed to form a tank which is partially filled with liquid refrigerant so as to leave a space above it, the air being substantially exhausted from said space and from the liquid refrigerant, so as to provide a high vacuum in the space above the liquid refrigerant into which it can expand when congealed.
10. 3. A cooling apparatus comprising two separated plates, a pipe bent back and forth between said plates, through which cooling medium is received, the plates being hermetically sealed so as to provide a tank, the distance between the opposed faces of the tank being greater than the diameter of the pipe, said tank being partially filled with a liquid refrigerant, the pressure inside of the tank being below atmospheric pressure so as to cause the sides of the tank to be pressed toward the pipe, and resisting means inside of the tank, in addition to the pipe and the liquid, for resisting the atmospheric pressure on the outside of the tank, so as to hold the sides of the tank apart and maintain the distance between them greater than the diameter of the pipe.
15. 4. The method of heat transfer from one member to another which consists in pressing the members toward each other in the presence of a liquid which forms a surface film on each of said members, said surface film being compressed between the members, as specified.
20. 5. The method of securing heat transfer from one metallic member to another not in direct contact with each other which consists in placing said members in the presence of a liquid having a vapor pressure whereby a film of condensed vapor collects on the surfaces of said metallic members and between the same, and forcing said metallic members toward each other to coalesce the surface films between the same, as specified.
25. 6. The method of heat transfer from one member to a second member which consists of enclosing one of the members within the other, partially filling the enclosure member with a liquid having a vapor pressure, and exhausting air to reduce the pressure within the enclosure member below that of atmospheric pressure whereby the sides of said enclosing member are pressed toward and against the other member thereby bringing surface films of condensed vapor on the adjacent contacting surface of said members together to form an intimate heat transfer bond between the same.
30. 7. The method of producing and maintaining thin films of high thermal conductivity between two members not in actual contact which consists in providing one member in the form of an enclosure, locating the other member within said enclosure between the sides thereof so as to substantially bridge the distance between said sides, partly filling the enclosure with a liquid having a vapor pressure under the conditions of use thereof, and exhausting air from the enclosure and sealing the same to thereby decrease the pressure within said enclosure below that of atmospheric pressure whereby the sides of said enclosing member are pressed toward the second member within the same causing films of condensed vapor at the adjacent surfaces of said members to be coalesced together, as and for the purposes specified.
35. 8. A refrigerating unit comprising a metal container having opposed flat sides, a refrigerating coil located within said container, the pipes of said coil extending between opposite sides of the container, said container having a cryohydrate therein which has an appreciable vapor pressure under the temperatures at which the refrigerating unit is used, said container and the cryohydrate therein being at a less pressure than the pressure of surrounding atmosphere whereby atmospheric pressure forces the side of the container inwardly toward the pipes or tubes of said coil, substantially as and for the purposes described.
40. 9. The herein described method, consisting of providing an enclosing container having opposed sides and with a coil located within said container between said opposed sides and substantially bridging across between said sides, filling said container partly with a liquid having an appreciable vapor pressure under the temperature conditions at which used, and removing air from the container to reduce the pressure therein below atmospheric pressure, as specified.
45. 10. The method of transferring heat from one metallic member to a second metallic member not in metallic contact with the first member which consists, in compressing films of condensed vapor on the adjacent and substantially contacting surfaces of said members, as specified.
50. 11. The method of heat transfer from one metallic member to another which consists in pressing the members toward each other, said members being coated with a condensed vapor surface film, whereby said surface films are compressed between the members, as specified.
55. 12. The method of providing a heat transfer structure which consists in providing an enclosing member partially filling said member with a liquid having a vapor pressure located within said member, a second member which extends between opposed walls of the first member and exhausting air to reduce the pressure within the enclosing member below atmospheric pressure, whereby air pressure from the outside forces the sides of the enclosing member inwardly, as and for the purposes specified.
60. 13. The process of producing a wringing film which consists in bringing two surfaces, having liquid films thereon, together under pressure.
65. 14. The process of producing a wringing film from a medium which is capable of changing from solid to liquid phase which consists in providing a first surface having said medium thereagainst, then forcing a second surface, likewise having said medium thereagainst, against the first surface, one of the said surfaces being restricted to a predetermined degree whereby unit pressure is increased as desired.
70. 15. The method of producing and maintaining thin films of high thermal conductivity between two members not in actual contact by the utilization of pressure.
75. 16. The method of transferring heat from one member to a second member not in actual contact with the first member by placing between the two members a thin film whose thickness is approximately two times the radius of molecular attraction.
80. 17. The method of transferring heat from one metallic member to a second metallic member not in metallic contact with the first member by placing between the metal members a film of condensed vapor whose thickness is approximately one and two-tenths of a millionth of an inch.
85. 18. The method of transferring heat from one

- metallic member to a second metallic member not in metallic contact with the first member by placing between the metal members a thin liquid film.
- 5 19. The method of forming a thermal conductor of high efficiency which consists in compressing two liquid barrier films together under a predetermined pressure to form a "wringing film."

20. A unit of the class described comprising a container having a heat carrying medium therein and a second container having a cryohydrate or the like therein, portions of said containers being in forcible contact, said portions being separated by a "wringing" film for the purpose described.

HERMAN W. KLEIST.
